UNITED STATES PATENT OFFICE.

FRÉDÉRIC MARIE CHAPLET, OF LAVAL, FRANCE, ASSIGNOR TO LA COMPAGNIE FRANÇAISE
DE L'AMIANTE DU CAP, OF PARIS, FRANCE.

PROCESS FOR THE INSULATION OF ELECTRIC WIRES AND CABLES.

No. 861,950.

Specification of Letters Patent.

Patented July 30, 1907.

Application filed May 4, 1905. Serial No. 258,839.

To all whom it may concern:

Be it known that I, FRÉDÉRIC MARIE CHAPLET, a citizen of the Republic of France, and a resident of Laval, France, have invented a new and useful novel 5 Process for the Insulation of Electric Wires and Cables, which process is fully set forth in the following specification.

The present invention is an improved process of insulating electric wires and cables, which consists 10 broadly in the superposition to the desired thickness of layers of fibrous materials, such as cotton, silk, asbestos, etc., each of said layers being applied parallel to and longitudinally of the wire or cable and separately closed around and smoothed thereon.

15 The method of applying the insulation parallel rather than spirally to the wire results in very pronounced advantages in the finished product. In the process of "taping" or winding the insulation spirally, the spirals overlap one another upon the wire, resulting in an irregular insulating envelop or covering, while in the present process of applying the insulation parallel to the wire in thin layers and compacting each layer as it is applied, this undesirable result is obviated, and a uniform, smooth, dense, compact and 20 adhering insulating coating or covering is attained.

25 The invention will be better understood by reference to the accompanying drawings, wherein—

Figure 1 is a diagrammatic view of an apparatus for carrying out the improved process; Fig. 2 is a similar 30 view at right angles to Fig. 1; and Figs. 3 and 4 are details of the smoothing or felting device.

Referring to the drawings, *a* is a drum on which are wound the wires or cables to be insulated, six wires being herein shown as so wound, and being numbered 35 from 1—6, respectively. As it is obvious that the operation for insulating is the same for each of the wires, it will be sufficient to refer only to, for example, wire 1. On leaving drum *a* wire 1 passes over a roller *b'* and in front of a roll *c'* over which latter passes a plurality of ribbons or layers, ten being shown in the drawings, though of course the number may be varied according to the thickness of insulation desired. These 40 ribbons or layers pass to the wires to be insulated from dividing drums *f* and *g* (Fig. 2) and if, for example, it

be desired to simultaneously apply to each of six wires 45 ten layers or ribbons of insulating material, it is obvious that sixty ribbons or layers must be suitably grouped for this purpose. When, now, wire 1 passes along parallel to roller *c'*, the first layer or ribbon begins to be applied thereto, and the first of a series of 50 smoothing devices (a smoothing device being supplied for each ribbon or layer of insulating material applied to each wire) felts the sliver or layer and closes the same longitudinally about the wire.

As shown in Figs. 3 and 4, each of these smoothing 55 or felting devices consists, essentially, of a pulley 7 suitably supported, as by collars 8 and 9, rotary movement being applied to said pulley by means of cable 10. Pivotedly mounted on pins 11 and 12, and arranged inside the pulley, are plates 13 and 14 which 60 are pressed against the wire or cable 1 by means of springs 15, as shown. The rubbing of the fibers of the layer or sliver against the plates effects the felting. Upon this first layer or sliver *d'*, which has been felted and closed around the wire by device *c'*, is applied 65 the second ribbon or layer *d*², which latter is felted by the smoothing device *e*²; and so on up to the last layer, the wire thus enveloped or covered being then wound upon a drum *h'*.

As has been before stated, the same operation is 70 taking place with wires 2, 3, 4, 5 and 6, which latter when covered with the insulated coating are likewise wound upon drums *h'*.

Having now particularly described and ascertained the nature of our said invention and in what manner 75 the same is to be performed, we declare that what we claim is:

A method of insulating electrical conductors by the superimposing to the desired thickness of thin layers of fibrous material, consisting in applying said layers parallel to and longitudinally of the conductor, and separately smoothing and compacting each of said layers as it is applied. 80

In testimony whereof I have signed this specification in the presence of two subscribing witnesses.

FRÉDÉRIC MARIE CHAPLET.
